UNITED STATES PATENT OFFICE.

MIRIAM J. TORRENCE, OF INDIANAPOLIS, INDIANA.

UTERINE SUPPORTER.

SPECIFICATION forming part of Letters Patent No. 760,823, dated May 24, 1904.

Application filed February 5, 1904. Serial No. 192,161. (No model.)

To all whom it may concern:

Be it known that I, MIRIAM J. TORRENCE, of Indianapolis, county of Marion, and State of Indiana, have invented a certain new and useful Uterine Supporter; and I do hereby declare that the following is a full, clear, and exact description thereof, reference being had to the accompanying drawings, in which like numerals refer to like parts.

- 10 The object of this invention is to provide a yielding and flexible support for the cup in uterine supporters. Heretofore the cup has been supported by a stiff stem, usually of hard rubber.
- 15 In the drawings, Figure 1 is a perspective view of said uterine supporter. Fig. 2 is a central vertical section through the cup and supporting stem. Fig. 3 shows a modified form of cup with the stem bent as it might 20 be in use and other parts in elevation.

In detail, 10 is the front member, and 11 the rear member, of a band or abdominal support. The two members are at the sides connected by elastic strips 12 and buckles 13. From 25 the members of the abdominal band or support a pair of rubber strips or tubes 14 extend, passing from the front to the rear members. They extend loosely, and therefore adjustably, through holes in a hard-rubber ball 30 or knob 15, that carries the flexible stem, on the upper end of which the cup 16 is mounted. The cup may be in any desired form, two being here shown. The flexible and yielding stem for the cup is herein formed of a 35 rather stiff coiled wire 17, with its two ends secured to threaded pins 18, one of which screws into the cup 16 and the other into the ball or knob 15. Over said spring a covering or rubber tube 19 is stretched that covers the metal parts 40 completely. A second rubber tube 20 is

stretched over the frame, and its ends also envelop the ends of the cup and ball or knob, so as to afford complete protection. It may be made of any flexible material that would be sanitary. It is thus seen that the stem is 45 yielding, as there is some space between each coil of the wire to permit it to yield, and the stem is also flexible. This enables the support to accommodate itself to the jolts of the organ while walking and afford relief therefrom, and while sitting it will bend also to accommodate itself to the position of the organ supported.

For cleaning the rubber covers may be removed and the cup and knob removed from 55 the spring, although this is usually needless, as the cover 20 is fully protective.

What I claim to be new and of my invention is—

1. In a uterine supporter, the combination 60 with the cup and knob, of a spiral spring, end pieces secured thereto adapted to be attached to the cup and knob, and a covering over said spring and the adjacent ends of the cup and knob.

2. In a uterine supporter, a cup with a threaded hole, a knob with a threaded hole, a spiral spring, an end piece secured to each end of the spring with a threaded pin to screw into the cup or knob, a covering for the spring 70 and end pieces, and an outer covering that overlaps the ends of the cup and knob.

In witness whereof I have hereunto affixed my signature in the presence of the witnesses herein named.

MIRIAM J. TORRENCE.
